GRINDING WHEEL TRUING APPARATUS

Lester J. Lalime, Providence, R. I., assignor to
 Brown and Sharpe Manufacturing Company, a
 corporation of Rhode Island

Application September 5, 1946, Serial No. 694,985

10 Claims. (Cl. 51—5)

1

The present invention relates to improvements in grinding wheel truing apparatus.

It is a principal object of the invention to provide a novel and improved grinding wheel truing apparatus having a plurality of truing devices adapted for truing the two relatively inclined peripheral grinding surfaces of a shoulder grinding wheel to cause these surfaces to be trued with accuracy and at an exactly predetermined angle with relation to one another.

It is a further object of the invention to provide a novel and improved truing apparatus of this general description adapted for truing the diameter and shoulder grinding surfaces of a shoulder grinding wheel, in which individual truing devices are supported at opposite sides of the wheel for the truing of the respective diameter and shoulder grinding surfaces, and in which provision is made for adjusting the relative positions of the wheel and truing devices in a novel manner to control with the high degree of accuracy required, the size of the included angle between the grinding faces.

The machine illustrated in the drawings as embodying in a preferred form the several features of the invention, comprises a shoulder grinding machine of the general type having a work table arranged for translatory movements, means for rotatably supporting the work thereon, a cross slide, and a rotary grinding wheel spindle having its axis of rotation at an angle to the axis of rotation of the work and to the cross slide on which the spindle is mounted for shoulder grinding.

The truing apparatus provided in accordance with the invention, comprises a truing device which is mounted at the front side of the grinding wheel for movement with the work support for truing the diameter peripheral grinding surface of the wheel, and a second truing device which is mounted at the rear side of the grinding wheel for truing the shoulder grinding surface of the wheel. The truing devices and grinding wheel are mounted for movement relatively to cause the truing tools to shape each of the diameter and shoulder grinding surfaces at the desired angle with relation to one another. The construction and arrangement of the machine including the truing devices is such that the plane of movement of each truing tool with relation to the grinding wheel is fixed, and the parts are rigidly supported to prevent any possibility of error in the operation of the truing devices.

Further in accordance with the invention,

2 means are provided for effecting a slight angular adjustment of the grinding wheel on the cross slide of the machine to correspondingly vary the size of the included angle between the diameter and shoulder grinding surfaces of the grinding wheel. This adjustment in effect permits a slight variation or adjustment of the slope of the shoulder grinding surfaces, while at the same time the desired accurate parallel relationship of the diameter grinding surface is maintained with relation to the axis of rotation of the work piece. The adjustment above described for controlling the size of the included angle between the diameter and shoulder grinding surfaces of the grinding wheel, has the advantage that it provides a readily available means to compensate for any errors which may exist in the mechanism for moving the truing tools in their respective directions.

20 With the above noted and other objects in view as may hereinafter appear, the several features of the invention consist also in the devices, combinations and arrangement of parts, which together with the advantages to be obtained thereby will be readily understood by one skilled in the art from the following description taken in connection with the accompanying drawings, in which Fig. 1 is a partial plan view of a grinding machine embodying in one form the several features of the invention; Fig. 2 is a fragmentary view in front elevation taken on the line 2—2 of Fig. 1, to illustrate particularly the truing device employed for truing the shoulder grinding surface of a shoulder grinding wheel set at a 45 degree angle to the work and to the grinding wheel supporting cross slide of the machine; Fig. 3 is a view in right side elevation of the grinding machine shown in Fig. 1; Fig. 4 is a plan view of a shoulder grinding machine similar to that shown in Fig. 1, except that the grinding wheel axis is set at a 30 degree angle from the axis of rotation of the work, and at a 60 degree angle from the cross slide on which it is supported, and in that a somewhat different form of truing device is provided at the rear side of the grinding wheel for the truing of the shoulder grinding surface of the wheel; Fig. 5 is a fragmentary view in side elevation taken on the line 5—5 of Fig. 4, illustrating particularly the truing device for truing the shoulder grinding surface of the arrangement shown in Fig. 4; and Figs. 6 to 10 inclusive, are diagrammatic views illustrating differently adjusted positions of the grinding wheel axis with relation to the cooperating diameter and shoulder grinding surface tru-

ing devices; Fig. 6 illustrating a grinding wheel having its axis set at a 45 degree angle for the grinding of a shoulder when the included angle is exactly 90 degrees, this being the arrangement shown in greater detail in Fig. 1; Fig. 7 being similar to Fig. 6, but with the grinding wheel axis tilted slightly to produce a slightly less than 90 degree included angle between the inclined grinding surfaces; Fig. 8 being similar to Fig. 6, but with the grinding wheel axis tilted slightly in the opposite direction to produce a slightly greater than 90 degree included angle between the inclined grinding surfaces; Fig. 9 illustrating a grinding wheel having its rotational axis set at a 30 degree angle from the axis of rotation of the work, and with the truing devices arranged to produce an included angle of 120 degrees between the inclined grinding surfaces; and Fig. 10 illustrating a grinding wheel with its axis of rotation set at 30 degrees from the axis of rotation of the work, and with the truing devices arranged to produce a 90 degree included angle between the inclined grinding surfaces.

Referring to the drawings, the illustrated machine comprises a base generally indicated at 10, a transversely movable slide support 12 which carries on a swivel mounting (not shown) a work table 13 having thereon a headstock 14 and a footstock 16, a grinding wheel support in the form of a cross slide 18 adapted for movement at right angles to the work table 13, and a grinding wheel 20 having its axis of rotation set at an angle to the plane of movement of the work. The work table is movably supported on a slideway comprising a V-shaped way 22 and a flat way 24, translatory movement being imparted to the table by means of feed connections which may be of ordinary description including a cylinder and a piston on a piston rod generally indicated at 26. The cross slide 18 is supported for sliding movement on a way generally indicated at 30, and is adapted to be moved toward and away from the work through connections which include a cross feed screw 32, a nut formed in a depending lug 34 on the cross slide 18 and a hand wheel 36 at the front of the machine. The grinding wheel 20 is mounted on a spindle 40 which carries at its other end a pulley 42 connected through belts 44 and a pulley 46 to be driven from an electric motor 48.

In accordance with a feature of the invention, the grinding wheel assembly above described, is supported on the cross slide 18 in a manner to permit of a slight angular adjustment of the grinding wheel with relation to the truing devices of the machine hereinafter to be described. To this end, a swivelling wheel spindle supporting plate 52 is mounted to turn about a swivel 54 on the cross slide 18, and is formed with an upwardly extending standard 56 which provides a bearing for the grinding wheel spindle 40 and with a supporting bracket 58 to which is secured the spindle motor 48. In the embodiment of the invention shown in Fig. 1 of the drawings, in which the grinding wheel spindle is set at approximately a 45 degree angle to the work, a mechanism for adjusting the angular position of the support 52 and the grinding wheel 20 is provided, which comprises an adjusting worm 60 and worm supporting shaft 62 which is mounted at the rear of the cross slide 18 in lugs 64, 66. The worm 60 engages the teeth of a worm gear segment 68 formed in the rear end of the swivel support 52. The swivel support 52 is rigidly secured in adjusted position with relation to the cross

slide 18 by means of a series of clamping machine screws 70, 72, 74, 76 and 78, which extend through slots in the swivel support 52, and are screw-threaded into the face of the cross slide 18. The slots referred to, are disposed circumferentially of the swivel 54 and permit the swivel support 52 and grinding wheel 20 to be adjusted angularly in each direction by a small amount approximating three degrees with relation to the cross slide 18.

In the embodiment shown in Figs. 1, 2 and 3 of the drawings, the grinding wheel spindle 40 and grinding wheel 20 are set with the rotational axis at a 45 degree angle with the work, and the grinding wheel is formed with two inclined surfaces including a diameter grinding surface 80 for grinding the peripheral surface of the work along the axis thereof, and a shoulder grinding surface 82 disposed at a 90 degree angle with relation to the diameter grinding surface 80. A truing device which may be of ordinary description, is provided for truing the diameter grinding surface 80, said device comprising generally a support 84 which is adapted to be mounted on the work table 13, and a truing tool 86. In accordance with the invention, a separate truing device is provided for truing the shoulder grinding surface 82, comprising a bracket 88 which is adapted to be mounted on the work table 13, and carries thereon a truing tool support 90 and a truing tool 92 adapted for engagement with the shoulder grinding surface 82 of the grinding wheel at the rear side of the wheel. As best shown in Figs. 1 and 2, the tool support 90 is mounted for adjustment on a guideway 94 formed on the support 88 at a 45 degree angle to the axis of rotation of the work, so that the truing tool may be adjusted along a line extending radially of the grinding wheel. An adjusting screw 96 having a knurled head 98 screw-threaded to the tool support 90 and supported against axial movement in a bearing 100 at the end of guideway 94 provides a convenient means of adjustment of truing tool 92.

The operation of the truing apparatus above described, and particularly illustrated in Figs. 1 to 3 of the drawings, may be briefly described as follows: The truing device comprising truing tool 86 for truing the diameter grinding surface of the wheel, and the shoulder truing device comprising truing tool 92 for truing the shoulder grinding surface, are located in their adjusted position preparatory for the truing operation which is performed while the grinding wheel is running by effecting a translatory movement of the sliding support 12 and work table 13 thereon to the right, so that the truing tools 86 and 92 respectively, are caused to engage with and true the respective diameter and shoulder grinding surfaces. In order that these surfaces, and more particularly the shoulder grinding surface 92 may be trued to precisely the desired angle, an adjustment or correction may be made in the angular position of the swivel support 52 and grinding wheel 20 mounted thereon by loosening clamping screws 70 to 78 inclusive, and thereafter by rotating the worm shaft 62 and worm 60. Diagrammatic Figures 6 to 8 inclusive of the drawings, indicate the manner in which this correction is made. Fig. 6 illustrates a truing operation under conditions in which the grinding wheel spindle 40 is set at exactly a 45 degree angle to the plane of movement of the work support, and in which the included angle between the diameter and shoulder grinding surfaces is exactly 90 degrees. In the event that inspection of work previously

completed on the machine, indicates that the grinding surface should be trued to a slightly smaller included angle, the swivel support 52 and grinding wheel assembly thereon may be swung slightly in a counterclockwise direction through a small angle. In the drawings, an adjustment of three degrees is indicated, and in which the grinding wheel spindle 40 is set from a 45 to a 48 degree angle with relation to the plane of movement of the work. Under these conditions the diameter grinding surface 80 will be trued in the normal manner to a plane parallel to the direction of movement of the work support, while the surface 82 will be trued to a less than 90 degree angle with the diameter grinding surface 80. Similarly, if the desirability of a greater than 90 degree included angle is indicated, adjustment of the grinding wheel assembly including the swivel support 52 and grinding wheel 20 may be effected in a clockwise direction, so that the grinding wheel spindle axis is set from 45 to 42 degrees with relation to the plane of movement of the work support. The diameter grinding surface 80 is again trued to a plane which is parallel to the direction of movement of the work support, while the shoulder grinding surface 92 is trued to a greater than 90 degree angle with the shoulder grinding surface 82. While in the drawings, a range of adjustment of three degrees in each direction is indicated, it will be understood that any range of adjustment larger or smaller than that indicated may be employed if so desired.

Figs. 4 and 5 of the drawings, illustrate a modified form of truing apparatus embodying the several features of the invention, which is adapted for the truing of a shoulder grinding wheel having the axis of rotation of the wheel set at a 30 degree angle from the plane of transverse movement of the work. In this form of the invention, the grinding wheel assembly including a grinding wheel 110, a grinding wheel spindle 112, pulleys 114 and 116, belts 118 and motor 120, are carried in a swivel support 122 with the spindle and grinding wheel set at a 60 degree angle from the plane of movement of the cross slide 18, and at a 30 degree angle from the plane of movement of the slide support 12 and work table 13. Angular adjustment of the position of the swivel support 122 and of the grinding wheel assembly thereon is obtained by means of a worm shaft 124 mounted at the forward end of the cross slide 18 in lugs 126, 128, and a worm 130 which engages with a worm gear segment 132 cut in the forward end of the swivel support 122. In the embodiment of the invention illustrated in Figs. 4 and 5, the swivel support 122 is rigidly clamped in adjusted position by means of a number of clamping screws designated at 134, 136, 138, 140 and 142 which extend through slots formed in the swivel support 122, and are screw-threaded into the cross slide 18.

The truing devices provided for this form of the invention, comprise the truing tool 86 carried on its bracket 84 on the work table 13 for the truing of the diameter grinding surface indicated at 144 of the grinding wheel 110. The mechanism provided for this form of the invention for truing the shoulder grinding surface of the wheel designated at 145, comprises a truing tool 146 which is supported and arranged for engagement with a portion of the grinding wheel diametrically opposite that engaged by the diameter surface truing tool 86. The truing tool 146 is mounted in a holder 148 adjustably supported in a housing 150

which is in turn mounted for sliding movement on ways 152 on a bracket 154 fixed to a transverse abutment 156 on the cross slide 18. The holder 148 is shifted radially toward the grinding wheel by means of a positioning screw 158 connected at its rear end by bevel gears 160 with a vertical shaft 162 which is in turn connected through bevel gears 164 with a horizontal actuating shaft 166. At its forward end the shaft 166 is formed with a hand wheel 168. For moving the tool holder 146 across the face of the grinding wheel, driving connections are provided in the form of a driving screw 170 which is screw-threaded into the base of the housing 150 and supported against axial movement to turn in a bearing provided in an upwardly extending flange 172 of bracket 154. The screw 170 is driven by means of an electric motor 174 through connections which comprise a belt 176 which passes around a pulley 178 driven from the motor 174 and around a pulley 180 carried on the screw shaft 170. Control of the motor 174 to cause the diamond tool holder 146 to dress the shouldered surface of the grinding wheel may be effected by any suitable electric circuit to the motor 174 as, for example, one which is responsive to switches on panel 184 (Fig. 4) with separate control buttons marked respectively "Stop," "Start" and "Reverse." The operation of truing the shoulder grinding surface of grinding wheel 110 is readily performed either during the operation of truing the diameter grinding surface or independently thereof.

The relationship of the grinding wheel 110 and the two truing tools 86 and 146 for the truing of the diameter grinding surface 144 and shoulder grinding surface 145 of the grinding wheel 110 set at a 30 degree angle from the work in accordance with the disclosure of Figs. 4 and 5, is particularly illustrated in diagrammatic form in Fig. 10. From an inspection of Fig. 10, it will be appreciated that in order to obtain a 90 degree included angle of the grinding surfaces 144 and 145, the truing tool 146 must move in a plane which is inclined 60 degrees to the axis of rotation of the wheel 110 and 30 degrees from the plane of movement of the slide support 12 and work table 13. A maximum rigidity of the supporting slide for the shoulder truing tool 146 is obtained by mounting the shoulder truing device directly upon the cross feed slide 18 which also carries the grinding wheel assembly. A truing device of the general type illustrated in Figs. 4 and 5, for the truing of the shoulder grinding surface of the wheel 110 is of general application and is capable of use in the manner herein described for any angular setting of the grinding wheel and grinding wheel spindle with relation to the cross feed slide and work support, and for the truing of relatively inclined diameter and shoulder grinding surfaces of whatever included angle. In the event that a truing device of this general type is employed for the truing of a shoulder grinding surface of a wheel set at a 45 degree angle as shown in Figs. 1 and 3, the tool support slide will then be supported on ways to move in a plane parallel to that of the work support. Any inaccuracy which might be found to exist in the angular relation of the machined supporting ways for the work table and the shouldered truing tool support is quickly and easily compensated for by a compensatory adjustment in the angular position of the swivel support 122 and the grinding wheel assembly mounted thereon.

Diagrammatic Fig. 9 of the drawings illustrates still another form of the shoulder grinding wheel

in which the wheel is set at a 30 degree angle from the plane of movement of the work support, and in which the shoulder surface truing tool and the diameter surface truing tool are maintained in parallel relation, to produce an included angle of 120 degrees between these surfaces. As in the instances previously discussed, an adjustment of the included angle to the most exacting standard is readily obtained by an appropriate angular adjustment of the grinding wheel assembly with its swivel support upon the cross slide 18.

While an illustrative form of the invention has been described in considerable detail, it will be understood that numerous changes in the construction and arrangement of the several parts and in the general application of the invention may be made, without departing from its principles and scope. The terms and expressions used herein have been employed as terms of description and not limitation.

What is claimed is:

1. In a grinding machine having a work support and a grinding wheel carriage supported on the machine for relative cross and translatory movement on the machine, rotary work supporting means on the work support, a spindle support mounted swivelly on the grinding wheel carriage at right angles to the directions of said cross and translatory movement, a grinding wheel spindle mounted on said swivel support, and a grinding wheel mounted on the spindle having relatively inclined abrading surfaces for work periphery and shoulder grinding, the combination of a truing attachment for truing said relatively inclined abrading surfaces to a predetermined included angle at a single setting of the grinding wheel and truing attachment, which comprises a work periphery truing tool mounted on the machine for movement in said translatory path and positioned for movement across said work periphery abrading surface in truing engagement therewith, a shoulder truing tool mounted in the machine to move in a linear path angularly related to said translatory path and positioned for movement across the work shoulder abrading surface in truing engagement therewith at the opposite side of the spindle from the work periphery truing tool, said shoulder truing tool being further supported from the machine for shifting movement transversely of said path against the shoulder abrading surface of the wheel, and means securing the swivel spindle support to the carriage in a position of fine angular adjustment to determine the included angle between the periphery and shoulder abrading surfaces.

2. In a grinding machine having a work support and a grinding wheel carriage supported on the machine for relative cross and translatory movement on the machine, rotary work supporting means on the work support, a spindle support mounted swivelly on the grinding wheel carriage at right angles to the directions of said cross and translatory movement, a grinding wheel spindle mounted on said swivel support, and a grinding wheel mounted on the spindle having relatively inclined abrading surfaces for work periphery and shoulder grinding, the combination of a truing attachment for truing said relatively inclined abrading surfaces to a predetermined included angle at a single setting of the grinding wheel and truing attachment, which comprises a work periphery truing tool mounted on the work support for movement in said translatory path for truing said work periphery abrading surface, a

shoulder truing tool support mounted in the machine to move in a linear path angularly related to said translatory path across the work shoulder abrading surface at the opposite side of the spindle from the work periphery truing tool, said shoulder truing tool support being further supported from the machine for shifting movement transversely of said path against the shoulder abrading surface of the wheel, a shoulder truing tool mounted on said shoulder truing tool support, and means securing the swivel spindle support to the carriage in a position of fine angular adjustment to determine the included angle between the periphery and shoulder abrading surfaces.

3. In a grinding machine having a work support and a grinding wheel carriage supported on the machine for relative cross and translatory movement, rotary work supporting means on the work support turning on an axis extending in the direction of said translatory movement, a spindle support mounted swivelly on the grinding wheel carriage at a right angle to the directions of said cross and translatory movements, a grinding wheel spindle mounted on said swivel support, a grinding wheel mounted on the spindle having relatively inclined abrading surfaces for work periphery and shoulder grinding, the combination of a truing attachment for truing said relatively inclined abrading surfaces to a predetermined included angle at a single setting of the grinding wheel and truing attachment, which comprises a work periphery truing tool mounted on the work support for movement in said translatory path for truing said work periphery abrading surface, a shoulder truing tool mounted on the work support at the opposite side of the spindle from the work periphery truing tool to move in said translatory path across the shoulder abrading surface, said shoulder truing tool being further supported on the work support to move transversely of said translatory path for adjustment of the shoulder truing tool against the shoulder abrading surface of the wheel, and means securing the swivel spindle support to the carriage in a position of fine angular adjustment to determine the included angle between the periphery and shoulder abrading surfaces.

4. In a grinding machine having a work support mounted for translatory movements in the machine, a rotary work supporting means on the work support turning on an axis extending in the direction of said translatory movement, a grinding wheel carriage mounted on the machine for cross feeding movement toward the work support, a spindle support mounted swivelly on the grinding wheel carriage on an axis at right angles to the carriage, a grinding wheel spindle on the swivel support, a grinding wheel on the spindle having relatively inclined work periphery and shoulder abrading surfaces, the combination of a work periphery truing tool mounted on the work support for movement in said translatory path for truing said work periphery abrading surface, a shoulder truing tool support mounted on the work support at the opposite side of the spindle from the periphery truing tool, a shoulder truing tool mounted on said shoulder truing tool support to move with the work support in said translatory path across the shoulder abrading surface, a guideway on the work support on which the shoulder truing tool support is adjustable along a path directed radially toward the axis of the grinding wheel spindle, actuating

means connected between the work support and shoulder truing tool support for moving the shoulder truing tool against the shoulder abrading surface of the wheel, and means securing the swivel support to the carriage in a position of fine angular adjustment to determine the included angle between the periphery and shoulder abrading surfaces.

5. In a grinding machine having a work support, rotary work supporting means on the work support, and a grinding wheel assembly including a grinding wheel carriage on the machine, a spindle support mounted swivelly on the grinding wheel carriage at right angles to the carriage, a grinding wheel spindle mounted on said swivel support, and a grinding wheel on the spindle having two relatively inclined work periphery and shoulder abrading surfaces, said work support and grinding wheel carriage being mounted on the machine for relative cross and translatory movements, the combination of a dressing attachment for dressing said relatively inclined abrading surfaces on the grinding wheel to the desired angles at a single setting which comprises a truing device mounted on the work support at the work engaging side of the grinding wheel spindle including a work periphery truing tool carried on the work support and movable relatively to the grinding wheel in a fixed path following the direction of said translatory movement for truing said work diameter abrading surface, a second truing device comprising a shoulder truing tool, a shoulder support on which said shoulder tool is mounted on the carriage movable in a fixed path for truing engagement with the other of said abrading surfaces at the opposite side of the grinding wheel from the work periphery truing tool, actuating means connected with said shoulder tool support to move said shoulder tool support and shoulder truing tool in said path, and fine gauge adjusting means controlling the angular position of the swiveling spindle support and grinding wheel spindle on the carriage.

6. In a grinding machine having a work support and a grinding wheel carriage supported on the machine for relative cross and translatory movement, rotary work supporting means on the work support turning on an axis extending in the direction of said translatory movement, a grinding wheel having relatively inclined work periphery and shoulder abrading surfaces, a grinding wheel spindle on which the grinding wheel is mounted, and a spindle support on the carriage on which the wheel spindle is supported for swiveling adjustment with relation to the directions of said cross and translatory movement, the combination of a dressing attachment for dressing the relatively inclined work periphery and shoulder abrading surfaces of said grinding wheel which comprises a work periphery abrading surface truing device on the work support at the work engaging side of the grinding wheel spindle including a truing tool responsive to the relative translatory movement of the work support and carriage for truing said work periphery abrading surface, a shoulder abrading surface truing device disposed at the opposite side of the grinding wheel spindle from the periphery abrading surface truing device comprising a shoulder truing tool support mounted in the machine for movement in a path of predetermined fixed direction, and a shoulder abrading surface truing tool mounted on the tool support for movement in said fixed path across said shoulder abrading

surface, and adjusting means controlling the swivel position of the swivel support and grinding wheel to vary the included angle between said relatively inclined work periphery and shoulder abrading surfaces.

7. In a grinding machine having a work support mounted in the machine for translatory movement, rotary work supporting means on the work support turning on a horizontal axis, and 10 a grinding wheel assembly including a grinding wheel carriage mounted in the machine for cross feeding movement, a spindle support mounted swivelly on the grinding wheel carriage on a vertical axis, a grinding wheel spindle mounted on 15 said swivel support to turn on a horizontal axis set at approximately a 45° angle to the direction of said translatory movement, and a grinding wheel on the spindle having relatively inclined work periphery and shoulder abrading surfaces, 20 the combination of a work periphery surface truing device comprising a work periphery abrading surface truing tool, and means supporting said tool on the work support at the work engaging side of the grinding wheel spindle, a shoulder 25 surface truing device comprising a shoulder truing tool support mounted on the work support, and a shoulder abrading surface truing tool mounted on the said shoulder truing tool support engaging a portion of the shoulder abrading surface of the grinding wheel at the opposite side 30 of the grinding wheel spindle from the work periphery abrading surface truing tool, and adjusting means controlling the angular position of the swiveling support and grinding wheel spindle on the grinding wheel carriage to vary the included angle of said relatively inclined abrading surfaces.

8. In a grinding machine having a work support mounted in the machine for translatory movement, rotary work supporting means on the work support, and a grinding wheel assembly including a grinding wheel carriage mounted in the machine for cross feeding movement, a spindle support mounted swivelly on the grinding wheel carriage on an axis at right angles to the carriage, a grinding wheel spindle mounted on said support, and a grinding wheel mounted on the spindle having relatively inclined work periphery and shoulder abrading surfaces, the combination 40 of a truing device comprising a work periphery abrading surface truing tool mounted on the work support and engaging a portion of the work periphery abrading surface of the wheel at the work engaging side of the grinding wheel spindle and acting to true said work periphery abrading surface, a shoulder abrading surface truing device disposed at the opposite side of the wheel spindle from the first mentioned truing device comprising a shoulder abrading surface truing tool, a shoulder truing tool support slidably 45 supported on the grinding wheel carriage for movement along a fixed path angularly related to the direction of said translatory movement of the work support, an electric motor, and driving connections from the motor to move said slidable support and truing tool across the shoulder abrading surface, and adjusting means controlling the angular position of the spindle support on the carriage to vary the included angle of said work periphery and shoulder abrading surfaces.

9. In a grinding machine a combination in accordance with claim 8 in which the shoulder truing device comprises a guideway on the spindle carriage, a shoulder truing tool supported on the guideway for movement along the line of movement followed by the truing tool across the shoul-

11

der abrading surface, and a tool holder movably supported on the shoulder truing tool support for adjustment in a direction perpendicularly toward and away from the grinding wheel axis, and actuating means on the machine connected with the work truing shoulder support operable to move the shoulder truing tool support in the guideway for truing said shoulder abrading surface.

10. In a grinding machine having a work support supported for translatory movement, rotary work supporting means on the work support turning on an axis extending in the direction of said translatory movement, and a grinding wheel assembly including a grinding wheel carriage supported on the machine for cross feeding movement toward the work support, a spindle support mounted swivelly on the grinding wheel carriage on an axis at right angles to the carriage, a grinding wheel spindle mounted on said support, said spindle being disposed on the carriage with its axis at approximately a 30° angle from the direction of said translatory movement, and a grinding wheel having relatively inclined work periphery and shoulder abrading surfaces, the combination of a work periphery abrading surface truing device comprising a work periphery abrading surface truing tool mounted on the work support, a shoulder abrading surface truing device disposed at the opposite side of the grinding wheel spindle from said work periphery abrading surface truing device comprising a shoulder abrading surface truing tool, a

12

support on which said shoulder surface truing tool is mounted, and a guideway on the grinding wheel carriage on which the shoulder truing tool support is movable to true said shoulder abrading surface at a 90° included angle with relation to the work periphery abrading surface of the wheel, actuating means on the machine connected with the tool support operable to move said tool support on its guideway, and adjusting means controlling the angular position of the wheel spindle support on the carriage to vary the included angle of said trued work periphery and shoulder grinding surfaces
